UNITED STATES PATENT OFFICE.

EDWARD MATTHIENSEN, OF MINNEAPOLIS, MINNESOTA.

COMBINATION PLOW AND PULVERIZER.

1,333,503.

Specification of Letters Patent.

Patented Mar. 9, 1920.

Application filed June 7, 1919. Serial No. 302,617.

To all whom it may concern:

Be it known that I, EDWARD MATTHIENSEN, a citizen of the United States, residing at Minneapolis, in the county of Hennepin 5 and State of Minnesota, have invented certain new and useful Improvements in Combination Plows and Pulverizers, of which the following is a specification.

My invention relates to plows and the 10 object is to provide a machine of such construction that it will plow the ground by digging and lifting the dirt up on an elevator from the upper end of which it is dropped and thus broken up, and then 15 rolled down by a drum which is also used as a rear support for the machine. The construction is clearly illustrated in the accompanying drawings, in which:

Figure 1 is a side elevation of the machine with a few portions broken away. 20 Fig. 2 is a top view of the machine shown in Fig. 1. Fig. 3 is an enlarged sectional detail view on the line 3—3 in Fig. 1. Fig. 4 is an enlarged sectional detail view on the 25 line 4—4 in Fig. 1.

Referring to the drawings by reference numerals, 1 designates a main frame which is supported at its front end by two wheels 2 and at its rear end by a drum or roller 3. 30 The wheels 2 are secured upon an axle 4 which is pivotally mounted to a brace 5 at a point 6 to one side of the center of the frame so that neither of the wheels 2 will run in plowed ground. Secured to the axle 35 4 is a tongue or pole 7 to which can be hitched horses for pulling the machine.

Upon the front portion of the machine is secured a gas engine 8 adapted to transmit power through a shaft 9, bevel gears 10, 11, 40 shaft 12, spur gears 13 and 14 and thus operate the elevator. The elevator consists of two heavy sheet metal walls 15 having near their upper ends journal members 16 adapted to rotate in bearings 17 secured to the 45 underside of the main frame 1. Within the journal members 16 is rotatably mounted a shaft 18 having secured upon one end the spur gear 14 and suitably spaced upon its middle portion two (or more if required) 50 apron supporting and actuating wheels or rollers 19. The apron consists of an endless chain of flat links 20 a number of which are provided with angular digging extensions or shovels 21. The apron is wide enough to 55 fill completely between the two elevator walls 15, and is stretched over the wheels 19

at the upper end and over a roller 22, journaled in the side walls, at its lower end. Said roller 22 (see Fig. 1), because of the fact that it is comparatively small in diameter, is provided with several flat surfaces so as to more efficiently engage the links of the apron. Two strips 23 preferably of angle iron are secured upon the inner sides of the elevator walls for the purpose of strengthening the same and also for supporting the upper run of the carrier apron. On each shovel or angle portion 21 of the apron are detachably secured a series of pointed digging members 24 secured by means of screws 60 or bolts 25 (see Fig. 4).

The lower end of the elevator is raised or lowered as desired by means of a hand lever 26 (see Figs. 1 and 2) having a dog 27 adapted to engage notches in a toothed sector 28 on which the lever is pivoted at 29. The lower end of the lever 26 is pivotally connected to a bail 30 secured at its ends near the lower end of the elevator walls. 75

The rear end of the frame 1, and thus also 80 the upper end of the elevator, can be raised or lowered by hand levers 31 having hand actuated dogs 32 adapted to engage notches in sectors 33 on which they are pivotally mounted at 34. The rear ends of the levers 31 are provided with slots 35 which are engaged by pins 36 secured in bars 37 which are vertically slid able in two casing members 38. The drum 3 is journaled at its ends at 39 (see Fig. 1) in the lower ends of 90 said bars 37.

The operation as well as the many advantages of the structure are obvious. With the machine moving forward, and with the engine and elevator running, the dirt (as 95 shown in Fig. 1) is dug up by the shovels 21 and diggers 24, and is carried up to the top of the elevator where it is dropped again thus loosening and pulverizing it. The roller 3, which it will be noticed is 100 wider than the elevator, then immediately rolls down the dirt again thus leaving a desired smooth surface. It is apparent that the dirt thus dug up and handled will be more thoroughly mixed than in the old way 105 of plowing where the dirt is merely turned over. Another advantage of plowing with this method is that because of the diggers 24 the plowed bottom is not left smooth but is corrugated, which is especially desirable because on hillsides the water is 110 then more easily retained. A particular

feature of the construction in this machine is shown in Fig. 3. The elevator is pivotally mounted to swing on the same center as the shaft 18 but is not trunnioned on it. 5 The journal members 16 have their bearing in the boxes or bearings 17, and the shaft 18 is journaled within the members 16. Thus the pressure against the elevator, caused by the forward movement of the 10 machine against the ground, will not tend to bind against the driven shaft 18, and the same will only have to overcome the resistance of the diggers on the carrier.

It is understood that the above combinations can be used in a variety of forms and structures if within the scope of the appended claims.

Having now therefore fully shown and described my invention, what I claim to 20 be new and desire to protect by Letters Patent is:

1. A machine of the class described consisting of a main frame adapted to be drawn, two front wheels and a rear drum 25 supporting said frame, a forwardly inclined elevator mounted within said frame forward of said drum, an endless carrier mounted in said elevator and adapted to be driven by an engine on the frame, spaced 30 shovels on said carrier adapted to dig and carry dirt up the elevator and drop the same in front of said drum.

2. A machine of the class described consisting of a main frame adapted to be 35 drawn, an elevator pivotally mounted upon said frame, an endless carrier and spaced shovels secured upon the same mounted within the elevator, an engine secured upon the frame, operative connection between the 40 engine and said carrier, a drum supporting the rear end of the frame and the same being wider than the width of the carrier, two

wheels supporting the front end of said frame one being placed within and the other without the transverse digging limits of 45 the endless carrier, as and for the purpose set forth.

3. A machine of the class described consisting of a main frame adapted to be drawn, an elevator mounted within the 50 frame, an endless carrier mounted within said elevator and means for actuating the same, spaced shovels secured upon said carrier adapted to dig, elevate and then release dirt as said elevator is being actuated 55 and the machine is moving forward, wheels supporting the front end of the frame, a transversely positioned drum supporting the rear end of the frame and being wider than said elevator, said drum being adapted 60 to roll down dirt as it is being released from the elevator, vertical casing members extending downwardly from the sides of the rear end of the frame, bars slidably mounted within said casing members, said drum 65 being journaled at its ends in the lower ends of said bars, hand levers connected to said bars for the purpose of lowering and raising the same.

4. A machine of the class described consisting of a wheel supported frame adapted 70 to be drawn, a longitudinally positioned inclined elevator comprising two side walls, upper and lower rollers journaled in said side walls, an endless carrier having spaced 75 shovels thereon, stretched over said rollers, journal members secured to said side walls and having their bearings in boxes secured to the main frame, a shaft journaled within said bearings and adapted to actuate said carrier; a source of power and operative connection between the same and said shaft. 80

In testimony whereof I affix my signature.
EDWARD MATTHIENSEN.
